UNITED STATES PATENT OFFICE

CHESLEY T. SMALL, OF ST. LOUIS, MISSOURI

PLUNGER SUPPORT

Original application filed February 17, 1926, Serial No. 88,765. Divided and this application filed February 25, 1928. Serial No. 256,993.

My invention relates to a plunger support for can filling machines or the like and is a division of application Serial No. 88,765 filed by me February 17, 1926.

5 One object of my invention is to provide an anti-friction support for the plunger which may be readily and accurately adjusted. Another object of my invention is to provide improved lubricating means for 10 the plunger bearing and the support.

In the accompanying drawings, which illustrate one form of support made in accordance with my invention, Figure 1 is a vertical section through a portion of a filling machine to which the support is applied; Figure 2 is an enlarged side elevation; and Figure 3 is an enlarged section taken on the line 3-3 of Figure 1.

The filling machine like that shown in my 20 prior application of which this is a division, has a central supporting shaft 1, on which a sleeve 2 is rigidly mounted by means of a set screw 3. On the sleeve is a flange 4 to which is secured a can table 5. Secured 25 to the under face of the can table is a casting 6 having a conical part 7 forming a shed to discharge waste material and having formed integral therewith plunger bearings 8 in which slide plungers 9. Mounted on 30 each of the plungers is an individual can support 10. In the lowest position of the plunger the top of the individual support should be flush with the top of the can table and this is secured by an adjustable stop 35 screw 11 carried in a lug on the bearing. Secured to the can support 10 is the shank 12 of a can guide. This shank prevents the can support and consequently the plunger from rotating with respect to the table.

40 The center shaft 1 rotates in a fixed sleeve 13 externally threaded. Vertical movable on the sleeve 13 is the hub 14 of an oil pan 15. The pan is prevented from rotating with respect to the shaft by a key 16 and is 45 adjusted in height by nuts 17 threaded on the sleeve above and below the hub. Secured in an annular groove in the bottom of the oil pan by clamping blocks 18 is a track 19 for controlling the vertical movement 50 of the plungers carrying the individual

can supports. The space between the casting 6 and the oil pan is closed, to prevent access of foreign material to the oil in the pan, by a sheet drum 20 riveted or otherwise secured to the casting and making sliding 55 contact with the periphery of the pan so as not to interfere with the raising and lowering of the pan and its track relative to the can table.

Formed in the lower end of the plunger 60 is a threaded bore in which is screwed the stem 21 of a ball cage 22 having formed in it a circular chamber 23 of the same diameter as the anti-friction ball 24 contained therein and running on the track 19. The ball is retained in position in the ball chamber by spinning over the edge of the cage at 25. The ball cage may be adjusted vertically in relation to the spindle by rotating it and so causing its stem to enter the bore 65 in the spindle to a greater or less distance. This may be accomplished by inserting a wrench bar in openings 26 in the periphery of the cage. These openings extend through the walls of the cage so as to permit the free 70 passage of the oil in the pan, which is filled with oil to about the height indicated by the broken line A-A in Figure 1, to the ball chamber. A lock nut 27 secures the cage 75 in position after it has been adjusted. In order that the oil in the ball chamber may 80 lubricate not only the ball but also the plunger bearing, I provide the plunger 9 and stem 21 with a central passage containing a wick 28 having a lateral extension 29 supplying oil to the plunger bearing. Formed in the top of the bearing 8 is an oil 85 groove 30 covered by a washer 31 to prevent surplus oil from running over onto the outside of the bearing and the cone 7 90 and thus causing powder or dust to adhere to the machine.

Having fully described my invention, what I claim as new and desire to secure by Letters Patent of the United States is:

95 1. In a device of the class described, the combination with a bearing, of a plunger stem sliding in said bearing, a ball cage carried on the lower end of said stem, an oil passage in said stem for lubricating the 100

bearing and terminating in the interior of said ball cage, and an anti-friction ball in said cage covering the inlet of said passage to form a valve therefor.

5 2. In a device of the class described, the combination with a bearing, of a plunger stem sliding in said bearing, a ball cage carried on the lower end of said stem, an oil passage in said stem for lubricating the bearing and terminating in the interior of said ball cage, an anti-friction ball in said cage covering the inlet of said passage to form a valve therefor, and an oil reservoir at the upper end of the bearing for accommodating 10 the surplus oil supplied by said valve.

15 3. In a device of the class described, the combination with a bearing, of a plunger stem sliding in said bearing, a ball cage carried on the lower end of said stem, an oil 20 passage in said stem for lubricating the bearing and terminating in the interior of said ball cage, a wick in said oil passage, and an anti-friction ball in said cage covering the inlet of said passage to form a valve there- 25 for.

25 In testimony whereof, I hereunto affix my signature, this 21st day of February, 1928.

CHESLEY T. SMALL.
